UNITED STATES PATENT OFFICE.

WILLARD E. PRESSLER, OF FORT WAYNE, INDIANA.

SLUG STACKER.

1,415,471.

Specification of Letters Patent.

Patented May 9, 1922.

Application filed April 22, 1921. Serial No. 463,615.

To all whom it may concern:

Be it known that I, WILLARD E. PRESSLER, a citizen of the United States of America, and resident of Fort Wayne, in the county 5 of Allen and State of Indiana, have invented certain new and useful Improvements in Slug Stackers, of which the following is a specification.

This invention relates to improvements in 10 stackers adapted for use as an attachment on machines for casting printers' leads, slugs, etc., and the object thereof is to provide means for preserving the slugs in an orderly rank upon the table of the casting 15 machine as they are cut successively from the slug bar so that they may be conveniently removed in groups without the necessity of stacking them by hand.

This object of the invention is accom- 20 plished by the construction illustrated in the accompanying drawings in which:

Fig. 1 is a plan view of that portion of a 25 slug casting machine of known type upon which slugs are cut from a slug bar, the present invention being shown applied thereto;

Fig. 2 is a detail perspective view of the 30 guide including a friction stop arranged thereon;

Fig. 3 is a detail perspective view of a 35 hinge block for the guide bar;

Fig. 4 is a detail perspective view of a slug 40 support;

Fig. 5 is a detail perspective view of the 45 parallel bar;

Fig. 6 is a detail perspective view of the 50 gauge block; and

Fig. 7 is a detail perspective view of the 55 adjustable supporting block for the parallel bar.

Similar characters of reference indicate 60 corresponding parts throughout the several views and having reference now to the same:

1 is a flat table forming part of a casting 65 machine of well known construction upon which slugs are cut from a slug bar 2 that is formed in a continuous strip by a portion of the casting machine which, being of well known construction, is not included in the 70 drawing. In the mechanism shown in Fig. 1, 3 is a longitudinally movable rod mounted in brackets 3', and 4 is a knife housing in which is positioned a reciprocable knife 5, the housing being fixed on the rod 2 by means 75 of a set-screw 6 so as to move therewith. A

bracket 7 is adjustably fixed on the rod 3 and supports a gauge block 8 that is adjustably fixed thereto. In the operation of the mechanism, as usual, the slug bar formed by the casting machine in a continuous strip 80 extends through the housing 4 and is progressed onto the table in a succession of advancing movements and contacts with and moves the gauge block 8 so that the rod 3 and knife housing are moved accordingly 85 to the position indicated in dotted outlines. When thus moved, the knife 5 is brought into the path of a reciprocating presser 9 which forces the knife inwardly so as to sever the bar 2 and form the slug 10. During the 90 operation the severed slug is moved away from the guide 11 out of the path of the slug bar 2 so that the slug bar may progress on to the table. When the knife is withdrawn the housing and its appurtenances automatically return to normal position in the usual manner. The operation described is of known practice, however, commonly the slugs as they are severed from the slug bar are permitted to fall over onto the table and accumulate in disorder, necessitating constant attention of the operator in arranging the slugs in stacks by hand.

The present invention is comprised of an attachment consisting of a guide 12 that is pivoted at one end to a hinge block 13 that is fixed to the housing 4 and is provided at its opposite end with a bracket 14 which is pivotally secured by a screw 15 to the end 95 of the table 1.

Also, a parallel bar 16 is arranged with one end engaged in a slot 17 in the gauge block 8 and with its opposite end pivotally connected to an adjustable block 18 on a supporting rod 19 which is arranged in connection with the table. The guide 12 and parallel bar 16 are adapted to swing upon their rear ends and maintain parallel relation with each other as their opposite ends are actuated respectively by the movable 100 slug cutting mechanism above described, so that the space between the guide and parallel bar is uniformly maintained during their movement.

A sliding bracket 20 is mounted upon the 105 guide 12 and has a tongue 21 that bears frictionally against the guide, and also an outwardly extending wing 22 is provided with an adjustable extension plate 23 which serves as a stop for the slugs as they are 110

formed and moved onto the table so that the slugs are held in position upon their edges.

In the operation of the invention the gauge block 8 is adjusted to a position according to the length of the slugs to be cut and the adjustable block 18 is positioned on the rod 19 so that the bar 16 will be parallel with the guide 12, the stop 22 is positioned at the inner end of the guide by moving the slide 20 accordingly. The casting machine and the cutting mechanism are then set in operation, and as the slugs are cut from the slug-bar and moved upon the table in successive order they are held endwise between the guide and parallel bar and bear sidewise against the stop so that they are retained in an orderly rank. The stop, being held frictionally in position by the slide, is moved accommodately backward as the slugs accumulate on the table without permitting the slugs to topple over in disarrangement. When the space between the guide and parallel bar becomes filled the rank of slugs is lifted by the operator in such groups as are convenient to handle at a time, and the stop is repositioned against the first of the remaining slugs.

What I claim is:

1. In an attachment for a slug machine having a table and a movable cutting mechanism, a guide having pivotal connection at one end with the table and at its opposite end with the cutting mechanism; a slide

having a stop thereon and being frictionally engaged in connection with the guide; and a bar arranged in parallel relation with the guide and having connection at one end with the cutting mechanism and pivotal support at its opposite end.

2. In an attachment for a slug machine having a table and movable cutting mechanism, a pair of parallel members extending over the table and having connection with the mechanism so as to be actuated thereby; and a stop having frictional support on one of the members and being adapted to hold the slugs in edgewise position upon the table as they accumulate thereon between the members.

3. In a stacker attachment for a slug machine having a table and a movable cutting mechanism, a pair of parallel members spaced apart and pivotally supported at one end at one side of the table and connected at their opposite ends with the movable mechanism to be actuated thereby; and a movable stop extending between the members and adapted to hold the slugs in edgewise position upon the table in the space between the members.

In testimony whereof I affix my signature, in presence of two witnesses.

WILLARD E. PRESSLER.
